UNITED STATES PATENT OFFICE.

GEORGE W. WEHMEYER AND BENJAMIN C. ALFORD, OF GOSHEN, IND.

CHURN.

SPECIFICATION forming part of Letters Patent No. 341,525, dated May 11, 1886.

Application filed December 29, 1885. Serial No. 186,979. (No model.)

To all whom it may concern:

Be it known that we, GEORGE W. WEHMEYER and BENJAMIN C. ALFORD, citizens of the United States, residing at Goshen, in 5 the county of Elkhart and State of Indiana, have invented certain new and useful Improvements in Churns; and we hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15 This invention relates to churning, and more particularly to that class of churns which have horizontal double dashers and are driven by concentric shafts.

This invention consists in the detailed construction and combination of the parts hereinafter fully described, and more particularly pointed out in the claims, whereby rotary motion is communicated to the dashers, and whereby the contents of the churn are kept at 25 any desired temperature.

In the drawings, Figure 1 is a side view of a churn embodying the invention, and having portions of the exterior casing broken away to show the interior mechanism. Fig. 2 is a 30 plan view of the churn with the cover removed. Fig. 3 is a detail view of larger size, taken on the line $x-x$ in Fig. 2, and showing the dashers, driving-pinions, and other parts in section.

35 Similar letters of reference indicate corresponding parts in all the figures.

A are the sides of the churn supported on legs a .

a' is a bent sheet-metal plate which forms 40 the bottom and ends of the churn.

The sides and ends of the churn are held together by means of the bolts a'' .

a'' is a spout, provided with a plug or other means for closing it, situated at the lower part 45 of the churn, so that the liquid contents can be run off when required.

B is a bent sheet-metal plate extending under the bottom of the churn, partly inclosing the sides of it, and thus forming the water-reservoir b . The upper edges of the plate B are 50 bent outward, forming the lips b' . The edges are then bent round, so as to form the tubes b''

and inclose the bolts b'' , which support the said reservoir. The bolts b'' extend through the sides of the churn and assist in keeping them 55 in position. The top of the plate B is kept some distance below the top of the churn, so that water may be poured into the reservoir b any time during the operation of making butter without disturbing the contents of the 60 churn. A spout, b'' , is provided at the lower part of the reservoir b , and is furnished with a plug or other means for closing it, so that the water can be retained or run off, as required. By these means the contents of the 65 churn can be kept at any desired temperature during the operation of churning.

C is the lid of the churn. It is provided with ribs c , which stiffen it and cause it to fit tightly.

D is the outer dasher, consisting of cruciform ends united by cross pieces d .

d' is a socket secured on the inside of one of the churn-sides A .

d'' is a pivot, which is secured to one end of 75 the outer dasher, D , and has its bearing in the said socket d' .

d'' is a plate provided with a square hole, and firmly secured to the opposite end of the dasher D .

80 d'' is a socket secured to the inside of one of the ends of the dasher, on the other side of it from the pivot d'' .

E is the inner dasher, consisting also of cruciform ends united by cross pieces e .

85 e' is a pivot secured to one end of the dasher E , and which has its bearing in the socket d'' on the end of the outer dasher.

e'' is a plate having a square hole in it, and firmly secured to the opposite end of the dasher E .

90 The dashers D and E are driven in opposite directions, and are preferably arranged to make the same number of revolutions in the same time. The outer dasher, D , is driven by 95 the pinion G , which is provided with a long hub, g , which extends through the side of the churn, and has a square portion, g' , on the end of it which engages with the square hole in the plate d'' , secured to the end of the said dasher. The inner dasher, E , is driven from the pinion H , which is provided with a square hole in it to fit the shaft.

100 I is the inner dasher driving-shaft, provided

with a squared portion, i , at one end, which engages with the square hole in the plate e^2 , secured to the end of the said dasher. The shaft I extends through the end of the dasher 5 D and the side of the churn, and is provided with the squared portion i' , upon which the pinion H is mounted. The outer end of the shaft I is journaled in the pinion-bracket cap, and is provided with the groove i^2 for the 10 locking-plate.

In order that the shaft I may be drawn back so as to free the inner dasher without disturbing the actuating-gear, the round part of it between the square portions i and i' is made 15 of a diameter not exceeding the smallest size of the portion marked i' , and the end i is made smaller than the said round part. The outer end, which has the groove i^2 in it, is made larger than the square portion i' , so that the 20 said portion may pass through the hole in the bracket-cap.

J is the pinion-bracket, secured on the outside of the churn by screws j , and further provided with the projecting portions j' . j' is the 25 bracket-cap secured to the said projecting portions j' of the bracket by the bolts j^2 .

K is the locking-plate for the shaft I. This plate has tapering dovetailed sides k , which slide in a corresponding recess in the cap j^2 , 30 and a slot, k' , which engages with the groove i^2 of the said shaft and prevents it from sliding.

L is the driving-shaft of the churn, provided with the crank-handle l for operating it. This 35 shaft is journaled in the bracket J and cap j^2 , and has secured upon it the pinions M and N. Of these the pinion M gears into the pinion H and drives the inner dasher.

P is an idle-pinion, which runs loose on a 40 pin, p , which projects from the side of bracket J. This pinion gears into the two pinions G and N, and thus secures the revolution of the outer dasher when the shaft L is rotated.

Churn-dashers and driving mechanism constructed according to the present invention 45 are more easily put together and taken apart

for cleaning or repair than those heretofore in use, besides being more effective and economical in action.

Having thus described our invention, what we claim as new, and desire to secure by Letters Patent, is—

1. In a churn, the combination of an outer dasher pivoted at one end to the side of the churn and provided with a square socket at 55 the other end, an inner dasher pivoted at one end to the said outer dasher and provided with a square socket at the other end, the pinion G, provided with a long square-ended hub, the shaft I, having square portions i and i' , 60 and the groove i^2 , the pinion H, having a square hole fitting the square portion i' , but allowing the said shaft to slide longitudinally, the bracket J, provided with the cap j^2 , having a dovetailed tapering recess, the locking-plate K, having dovetailed tapering sides, and the slot k' , and mechanism for revolving the 65 said pinions in opposite directions, substantially as and for the purpose set forth.

2. In a churn, the combination of the driving-shaft L, provided with means for revolving it, the pinions M and N, secured upon the said driving-shaft, the idle-pinion P, running loose on pin p , the pinion G, provided with a square-ended hub, the shaft I, having square 75 portions i and i' , and the groove i^2 , the pinion H, fitting the square portion i' , but allowing the said shaft to slide longitudinally, the bracket J, the cap j^2 , having a dovetailed tapering recess in it, the locking-plate K, fitting the said recess and engaging with the groove i^2 in the shaft, the inner dasher, E, operated by the shaft I, and the outer dasher, D, operated by the hub of the pinion G, substantially as and for the purpose set forth. 80

In testimony whereof we affix our signatures in presence of two witnesses.

GEORGE W. WEHMEYER.
BENJAMIN C. ALFORD.
